UNITED STATES PATENT OFFICE

ROBERT C. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed August 3, 1922. Serial No. 579,448.

My invention relates to hoisting mechanisms and more particularly to hoisting mechanisms of the portable type.

An object of my invention is to provide an improved hoisting mechanism. Another object of my invention is to provide an improved hoisting mechanism of the portable type particularly adapted for operation by steam. A still further object of my invention is to provide an improved steam hoisting mechanism of a very compact type in which excessive heating of the parts which must be manipulated may be avoided, and in which leakage may be reduced and discharge of the exhaust steam facilitated. Other objects and advantages of my invention will hereinafter more fully appear.

In the accompanying drawings I have shown for purposes of illustration one form 20 which my invention may assume in practice.

In these drawings,—

Fig. 1 is a central vertical longitudinal section through a hoisting mechanism constructed in accordance with the illustrative 25 embodiment of my invention.

Fig. 2 is a similar section with the drum turned through 90° and with parts shown in elevation.

In the illustrative embodiment of my improved hoisting mechanism, the same comprises a base frame 1 upon which at opposite ends there are mounted hangers 2 and 3. Rotatably mounted within the hanger 2 is a member 4 which will be more fully described later, this member 4 having a sleeve or flange 5 formed thereon which is journaled in the hanger 2. The hoisting mechanism also comprises a drum 6 at whose opposite ends are arranged heads 7 and 8, these heads being respectively provided with stub shafts 9 and 10 which are journaled in bearings 11 and 12, the former of these bearings being arranged within the sleeve 5 while the latter is arranged directly within the hanger 3. Within the drum 6 and spaced therefrom for the greater portion of its periphery is an engine casing 13, the casing being separated by an air space 14 from the drum shell proper whereby the heat of the steam admitted to the motor casing is not

transmitted in any considerable quantity to the drum and so the drum and the cable wound thereon are not so difficult to handle. The motor casing 13 has its opposite ends closed by head members 15 and 16, the head member 16 being within the body of the drum 6 and the head member 15 being arranged intermediate the casing and the head 8. Within the casing 13 there are arranged a pair of rotor bores or chambers 17 and 18, which bores are arranged with their axes parallel to the axis of rotation of the drum and intersect each other along a central axial plane. Within the rotor chambers 17 and 18 are rotors 22 and 21, these rotors being provided with intermeshing tooth blades 22' and 21' which cooperate on rotation of the rotors to form pockets whose volume increases as rotation takes place. The rotors are of slightly less length than the chambers 17 and 18 so that at the ends of the rotors there are formed exhaust spaces 23 and 24, which spaces will be referred to hereafter, the fluid escaping to these spaces from the tooth pockets when the tooth blades run out of mesh. The rotors 21 and 22 are mounted upon shafts 25 and 26 which are journaled respectively in bearings 27 and 28 and 29 and 30. For the purpose of preventing the leakage of steam along the shafts of the rotors and so interfering with the lubrication of these bearings, I arrange brass or other suitable housing members 32 around the shafts 25 and 26 and inside of the several bearings. Within these housing members 32 are carbon rings 33 which are of such size as to fit quite closely the periphery of the shafts 25 and 26 and these are held up by spring pressure and by exhaust pressure, the spring pressure being furnished by springs 34 lodged in cavities 35 in the members 32. Motive fluid is admitted to the rotors by way of an axial passage 36 arranged in the stub shaft 10, the stub shaft 10 being surrounded by a stuffing box 37 to prevent leakage of steam around its outside. The passage 36 communicates with the passage 38 extending radially within the head member 8, and this passage connects by a passage 39 formed in the casing 13 with an inlet 100

passage 40 opening into the rotor chambers at the point of inception of the expanding pockets. Exhaust takes place by way of passages 42 and 43 communicating with the exhaust chambers 23 and 24, these passages communicating with a longitudinally extending passage 41 formed in the casing 18 which communicates by a passage 44 and a radial passage 45 with a passageway 46 which leads to exhaust, the passage 46 being formed in the stub shaft 9 and the latter being surrounded by a stuffing box 47.

Rotation of the drum is accomplished by the following means. The shaft 26 upon which the rotor 22 is mounted carries at its end a pinion 48, which pinion meshes with an internal gear 49 which is carried upon a shaft 50 journaled in bearings 51 and 52, respectively, formed in the heads 16 and 7. It is to be noted that the bearing 51 is positioned relative to the motor housing as by a bearing bracket 70, having a centering lug 71 disposed within a recess 72 formed in the head 16 and coaxial with the drum axis. Formed upon the shaft 50 is a pinion 53 which meshes with a gear 54 keyed to a shaft 55, which shaft is journaled in a bearing 56 within the head 7. At the outside of the head 7 the shaft 55 carries a pinion 57 which meshes with a gear 58 rotatable upon a fixed stud 58' on the head 7. The gear 58 meshes with an internal gear 59 carried upon a flange 60 formed upon the member 4. It will accordingly be evident that when the member 4 is held stationary, operation of the motor will cause the gear 58 to roll around upon the interior periphery of the gear 59 and so cause rotation of the drum. The flange 60 is also provided with a braking surface 61 with which a brake band 62 operated by suitable manual control means 63 cooperates in holding the member 4 stationary or releasing it at will. At the opposite end of the drum 6 is a radially extending flange 64 upon which a cylindrical surface 65 is formed for cooperation with the brake band 66 controlled by manual operating means 67.

From the foregoing description the mode of operation of this mechanism will be already clear. Fluid having been admitted through the passage 36 will pass by way of the passages 38, 39 and 40 to the pockets formed upon the periphery of the rotors and rotation of the rotors will take place. The exhaust fluid released by the running out of mesh of the tooth blades forming the pockets will enter the exhaust chambers 23 and 24 from which it will pass by the ports 42 and 43 to the passage 41 and thence by the passages 44 and 45 to the exhaust passage 46. Rotation of the rotor 22 will cause rotation of the shaft 26 and so of the driving pinion 48 which will in turn drive the internal gear 49 and so the pinion 53. The

latter will drive the gear 54 and so the pinion 57 and the latter in its turn will drive the gear 58 which meshes with the gear 59. Therefore, depending upon whether the member 4 is held stationary or not, the drum will be rotated while the motor runs, or the drum may remain stationary while the motor still continues to run. By reason of the air spaces and the arrangement of the ports and passages described, there will be but little of the heat from the steam employed in the motor transmitted to the drum and the rope wound thereon, and accordingly it will be possible to handle the hoist and the haulage cable without danger of injury from burns.

While I have in this application specifically described one form which my invention may assume in practice, it will be understood that this form of the same is shown for purposes of illustration and that the invention may be modified and embodied in various forms without departing from its spirit or the scope of the appended claims.

What I claim as new and desire to secure by Letters Patent is:

1. In a hoisting mechanism, in combination, a rotatable winding drum, a driving motor therefor disposed within said drum and held in immovable relation thereto, said motor having a motor shaft offset from the axis of said drum, and driving connections between said motor shaft and drum comprising reduction gearing including a transmission shaft having an end adjacent said motor, a detachable bearing bracket for supporting said end of said shaft, and means to position one end of said bearing on the adjacent end of the motor casing.

2. In a hoisting mechanism, in combination, a rotatable winding drum, a steam actuated motor disposed therein and held in immovable relation thereto, said motor having a plurality of intermeshing motor rotors, one of said rotors having a power shaft, and driving connections between said power shaft and drum including a pinion carried by said shaft, a plurality of sets of coaxial gears, one gear of each set meshing with each other while the remaining gear of one set comprises an internal gear meshing with said pinion, and fluid supply and exhaust connections for said motor including passage forming means extending from said motor to a point beyond said coaxial gears.

In testimony whereof I affix my signature.

ROBERT C. OSGOOD.
